UNITED STATES PATENT OFFICE.

CANOVA TITUS CAGLE, OF BEERSHEBA SPRINGS, ASSIGNOR OF ONE-HALF
TO JOSEPH L. WEAKLEY, OF NASHVILLE, TENNESSEE.

SPOOL-HOLDER.

SPECIFICATION forming part of Letters Patent No. 358,727, dated March 1, 1887.

Application filed October 21, 1886. Serial No. 216,877. (No model.)

To all whom it may concern:

Be it known that I, CANOVA TITUS CAGLE, of Beersheba Springs, in the county of Grundy and State of Tennessee, have invented a new and useful Improvement in Spool-Holders, of which the following is a specification.

My invention consists in a holder for spools or balls of thread, twine, flax, worsted, yarn, or silk, which may be adjusted to support spools or balls of any size, and which is provided with means for securing it to the front of the dress-body of the person using it, and which is further provided with a strip or cushion for holding pins, all as will be hereinafter fully described and claimed.

Referring to the accompanying drawings, Figure 1 shows my improvement as in use. Fig. 2 is a perspective view of the device. Fig. 3 is a sectional view of same, and Fig. 4 is a detail view.

The same letters of reference indicate corresponding parts in all the figures.

Referring to the several parts by letter, A represents the base of my improved spool-holder, which is cut out of light metal in any ornamental or desirable form, having formed integral with it at one end an outwardly-extending arm, B, the outer end of which has the stud B', which forms a pivotal bearing for one end of the spool. Toward the other end of the base-plate A are struck up from the base itself the two parallel rows of inclined teeth C, beneath which slide the side edges of the adjustable slide D, which carries the arm E, having at its upper end the stud E', which forms the pivotal bearing for the other end of the spool. The slide D has formed in its edges, on the upper side thereof, the depressions D', in which the ends of two of the teeth C rest, thus securing the slide in the position in which it may be adjusted.

It will be seen that the adjustable arm E may be moved to enable the holder to receive and hold in operative position any length of spool or ball. The back of the base-piece has secured to it a pin, G, which is hooked into the front of the dress-body of the person using it, the spool or ball being thus always held in place, preventing it from falling on the floor

or getting lost when the person moves or arises. 50 The holder can thus be used in sewing, embroidery, knitting, quilting, crocheting, and all fancy work where thread, twine, cord, silk, worsted, yarn, &c., are used.

To the base A is secured in a convenient position a small cushion, as H, in which pins may be carried, being thus always conveniently in reach when required. The studs which form pivotal bearings for the ends of the spool or ball are made round in cross-section 60 to cause the spool to turn smoothly and freely on them.

To place the spool or ball in position, the movable arm E is slid out until the spool can be placed between the arms, with the stud of 65 the fixed arm in one of its ends, when the arm E is moved back until its stud enters that end of the spool a sufficient distance, when the adjustable arm is held in position by the ends of two of the teeth C resting in the depressions 70 D' of its slide D, as described.

From the foregoing description, taken in connection with the accompanying drawings, the construction, operation, and advantages of my invention will be readily understood.

My invention is simple, cheap, and strong in construction and very convenient and efficient in use. It is also preferred to provide a thimble-support, I. In the construction shown this support is formed of a wire attached at one end to the plate or base A, bent into hook form, and having at its outer end sufficient spring or tension to clamp a thimble when placed thereon, as shown.

Having thus described my invention, what I 85 claim, and desire to secure by Letters Patent, is—

1. The combination, with the base-plate having the retaining-pin and the stationary arm provided with the stud, of the adjustable arm 90 having the stud, as set forth.

2. The combination, with the base-plate having the retaining-pin, the stationary arm provided with the stud, and the parallel rows of teeth, of the adjustable arm having the stud 95 and the sliding base-piece.

3. The combination, with the base-plate having the retaining-pin, the stationary arm pro-

vided with the stud, and the parallel rows of teeth, of the adjustable arm having the stud and the sliding base-piece having the depressions, as described.

5 4. The plate A, having a retaining-pin and bearings for the spool and provided with the thimble-holder formed of a wire secured at one

end to the plate, bent into hook form, and having a tension, whereby to clamp a thimble, substantially as set forth.

CANOVA TITUS CAGLE.
